COLOR TELEVISION TUBE
Bernice Ray Winge, 39 E. Surrey Drive,
Charleston Heights, S.C. 29405
Filed Dec. 13, 1963, Ser. No. 330,283
4 Claims. (Cl. 178—5.4)

This invention relates to an improved picture tube especially adapted to color television, and compatible to black and white reception. The improved tube may be used with color television receivers on the market in conjunction with the circuitry shown as part of this invention. The invention is especially useful in picture tubes having a single electron gun, but has other applications.

In the present system, commonly called the "Tri Dot" system, a battery of three electron guns are so positioned that their beams converge at 60 degree angles through tiny apertures placed directly in front of the screen. On the screen proper, and placed in proper geometric relation, are three dots of phosphor, representing three primary colors; red, blue and green, at which the beams are aimed. Each electron gun must be aimed at its respective color, and a high degree of accuracy must be maintained for proper operation. To maintain this accuracy, or proper convergence, many complex electronic circuits and critical positioning of elements are necessary. Even so, only a small portion of the electrons penetrate the apertures, resulting in relatively low efficiency, and necessitating higher currents and voltages from the power supplies. Another serious shortcoming of the present three gun tube is its susceptibility to magnetic fields, requiring special shields and components which are often ineffective should the receiver be moved to a different location. Still further, the neck of such present tube is large, requiring a special yoke design, and high currents.

Therefore, an important object of this invention is to eliminate the problem of convergence by providing an improved single gun color television tube capable of practical operation.

Another object of this invention is to provide a more efficient color tube requiring lower voltages and currents, and using less components of simpler design.

Another important object is to greatly lessen the susceptibility of a color tube to magnetic fields, including the earth's magnetic field, and reduce the requirements for special shields, magnets, coils and the like.

Still another object of the invention is to produce a tube of a single neck design permitting the use of smaller yokes, thus relieving further the load on the power supply, through a tube of relatively simple design.

Another important object of this invention is to provide a tube affording a greater degree of color purity across the entire scan.

Still another object of this invention is to provide the user of the television set a simple and easy device to operate.

The construction designed to carry out the invention will be hereinafter described, together with other features thereof.

The invention will be more readily understood from a reading of the following specification and by reference to the accompanying drawings forming a part thereof, wherein an example of the invention is shown and wherein:

FIGURE 1 is a schematic side elevation illustrating a tube, together with a block schematic diagram illustrating electronic components constructed in accordance with the present invention.

FIGURE 2 is an enlarged elevation illustrating the first molded plate and grid assembly, and

FIGURE 3 is an enlarged elevation illustrating the

2

arrangement of the phosphor color dots and the second molded plate.

Referring now to FIGURE 1, the tube bell portion 71 has a neck 70 and a viewing screen 6. An electron gun 5 including a heater 1, a cathode 2, a control grid 3, and accelerating and focus grids 4 and 5 is positioned within the neck 70. The envelope and gun may be of any suitable design, but are preferably of the same general design of standard tubes. A deflection coil 8 is placed around the neck of the tube to provide deflection of the electron beam 28. The driving voltages for the coil 8 will be supplied from the existing receiver for horizontal and vertical deflection.

The expanded bell of the tube 71 is internally covered 15 with a first conductive coating, illustrated at 10. The bell of the tube 71 is also coated internally with a second conductive coating 11, which is insulated from coating 10. The purpose of the conductive coatings is to electrostatically focus the electron beam 28, and to provide an acceleration voltage on the coating 10 and a deceleration voltage on the coating 11. The electron beam will ultimately arrive at the face of the viewing screen 6, but in so doing will pass through the holes in the first molded plate 20, which has a conductive coating 21 on the front side thereof. The coating 21 is connected to a suitable voltage source 74 to further control the beam 28 adjacent the plate 20. The beam will also pass through the color gating grids 22, 24 and 26, the holes in the second molded plate 30, and will strike the appropriate color dots 32, 34 and 36. The conductive coating 21, molded plate 20, color gates 22, 24 and 26, molded plate 30 and the color dots 32, 34 and 36 are sandwiched together in register, but are shown schematically as an exploded view for purposes of illustration.

Referring to FIGURE 2, it will be noted that the holes are preferably octagonal in shape to permit maximum penetration by the electron beam. The side of the plate facing the electron gun has a conductive coating 21 to conduct away the electrons that fail to enter the holes.

FIGURE 2 shows the molded plate 20, illustrating a preferred arrangement of the color gating grids 22, 24 and 26 with respect to the insulating material of the plate 20. The color gate grids may be of an extremely fine wire mesh inserted in the holes 22, 24 and 26 woven with 500 to 1,000 ends per inch, such as the grid used as a shadow mask in the iconoscope, or may be deposited on the inside surfaces of the holes. The grids are divided into three groups in the pattern shown in FIGURE 2 with proper electrical connections. The grids marked R (red) in FIGURE 2 are terminated at 23, the grids marked B (blue) are terminated at 25, and the G (green) grids are terminated at 27. The color signals from the television receiver will be applied to the conductors 23, 25 and 27 in a specific manner to be fully discussed below.

It will be noted that any electrons arriving at the plate 20 from the beam 28 must enter the holes and pass through the influence of the color gating grids 22, 24 and 26. It will also be noted that the respective holes also designated R, B and G are positioned in a specific manner in a triangular sequence. The electron beam 28 will be focused so that it will scan two horizontal lines of holes at a time (such as line A and line B in FIGURE 2), and will cover an area defined by three holes (such as holes X, Y and Z, FIGURE 2). The electron beam 28 will traverse the holes from left to right in FIGURE 2 so that as the beam 28 leaves a hole, it will pick up another hole of the same color.

Situated directly in front, and in register with molded plate 20 is a second molded plate 30 constructed of insulating material. The construction of molded plate 30

is illustrated in FIGURE 3. Referring to FIGURE 3, it will be seen that the bottoms of the holes of plate 30 are filled with phosphor 32, 34 and 36, respectively. The color of the phosphor agrees with the arrangement of color holes as shown, that is, all R holes are filled at the bottom with red phosphor 32, all B holes with blue phosphor 34, and all G holes with green phosphor 36. The bottom of the holes in FIGURE 3 constitute an integral part of the face of the viewing screen.

Thus, a picture tube is constructed in a conventional manner as regards the envelope and the electron gun, and is operated as a conventional cathode ray tube. A color gating system of electrodes near the face or screen of the tube is also provided. Electrons arriving from the beam 28 to the color gating system will be forced to enter a hole to reach a phosphor dot. Once an electron enters a hole, it is trapped so as to eliminate color spreading. After electrons enter a hole, and before they arrive at the phosphor, they must pass through a color gating grid (22, 24 or 26) where they may be diminished in number, or completely stopped, depending upon the value of the gating voltage in relation to the color signal, which is supplied by the receiver according to the requirements of the picture transmitted.

Another very important consideration is the control of the quality of color reproduction. Referring again to FIGURE 1, it will be noted that a standard Y signal is applied to the cathode. The Y signal is taken directly from the receiver and is used to control the density of the electron beam 28 and hence the brightness of the picture. In color television circuits this signal is often referred to as the "black and white component." The voltage of the Y signal is a function of the combined amplitudes of the incoming signals, and will vary the density of the electron beam 28 accordingly. When the electron beam is projected toward the screen in various densities, due to multiple colors increasing or decreasing the Y signal, it is desirable that the gating grids 22, 24 and 26 compensate for the changes in density to maintain true color reproduction. The electron flow through a control grid increases if the incoming electrons increase in number, even though the bias on the grid remains constant. Therefore, an increase in the Y signal due to the addition of multiple color signals, for example, would increase the intensity of all the colors reproduced due to an increased number of electrons reaching the screen, thus distorting the colors. The following discussion describes a solution to this problem in accordance with the invention.

Referring again to FIGURE 1, the arms of potentiometers 46, 47 and 48 are connected to the three color grids 26, 22 and 24 through resistors 52, 54 and 53. The potentiometers 46, 47 and 48 are so adjusted as to provide a standard relative bias on the color grids so that the red grid 22 is biased, for example, at 30%, the blue grid 24 at 11% and the green grid 26 at 59%. In the absence of any color signal, the three grids will control electrons in this percentage, and compatible black and white will be produced. The potentiometers 46, 47 and 48 are in effect contrast controls.

It will be noted that the potentiometers 55, 56 and 57 are common to one side of a high voltage supply, and resupply the phosphor color dot groups 32, 34 and 36, respectively, through leads 33, 35 and 37. The purpose of the potentiometers is to adjust for the sensitivity of the particular color phosphor and produce exact color hues. These potentiometers correspond to the brightness controls on conventional television sets.

Assuming, for example, that a single color, red, is received. The red signal will appear simultaneously at the input of the Y amplifier 12 and the R amplifier 14. The Y amplifier 12 will amplify and invert the signal and apply it to the cathode as a negative going signal. The control grid is held at a proper bias by power supply 3a to keep the picture tube in conduction. The negative

going Y signal will increase the electron stream 28 from the single electron gun assembly, and the density of the electron stream will be proportional to the applied voltage from the Y amplifier 12.

The red signal is also applied to the input of the R amplifier 14 and receives normal amplification. It is taken out as a negative going signal and applied to the input of R controlled amplifier 14a. Here again, it receives normal amplification, and is taken out as a positive going signal fed through the conductor 23 to the red color grids 22, driving them positive. The R signal is also applied to the R amplifier 58. Here it is amplified and fed as a negative going signal to a matrix arrangement including the resistors 39, 40, 41 and 42. The matrix system is calculated so as to proportionately feed the succeeding amplifiers according to the color optical ratio, stated as red 30%, blue 11% and green 59%. The output from the resistors 39 and 40 operates a matrix bias generator 62 which passes the signal to bias down the G (green) controlled amplifier 16a by lead 68. This may be accomplished by applying the signal to the screen grid of the amplifier 16a or to a second control grid. Thus, the output of amplifier 16a normally fed to the green color grids 26 by lead 27 is greatly reduced.

Also, the output of matrix bias generator 62 is fed by the lead 65 to the potentiometer 44. From the arm of the potentiometer the output is fed through the capacitor 50 to the green color grid 26. Since the output is a negative going signal, it will also bias down the green signal. Thus, the green phosphor is blanked, and will not light. The output from the R amplifier 58 is applied to the matrix amplifier 63 through matrix resistors 41 and 42 producing a negative signal applied to the B (blue) controlled amplifier 15a through lead 69 to reduce its gain. Thus, the output of B controlled amplifier 15a, normally fed to the blue color grids 24 by lead 25, is greatly reduced. The signal is applied to the potentiometer 45 through lead 66. The signal is taken from the arm of the potentiometer 45, passed through the capacitor 49 and fed to the blue color grid 24 to bias it out of conduction. Thus, it is seen that when a particular color appears alone, it will turn on its color amplifiers, and cut off the other two color amplifiers. The above discussion for red, applies similarly for each of the other two colors.

Consider now the action of the circuits when two color signals, red and blue, for example, are received. The Y signal is increased in accordance with the addition of R and B signals, and the density of the electron beam 28 increases correspondingly. Since more electrons would normally arrive at the red color grid 22, the red would deepen. This is what presently distorts the colors in color picture tubes. Referring again to FIGURE 1, as the B signal is added to the Y amplifier 12 and the B amplifier 15, it is at the same time added to the B amplifier 60. The output of B amplifier 60 is matrixed through resistors 37 and 38 to the matrix amplifier 61 and the negative going signal from matrix amplifier 61 used to bias down the red amplifier 14a by lead 67. Also, the output of matrix bias amplifier 61 will bias down the red color grid 22 through lead 64, through potentiometer 43, and from the arm of potentiometer 43 through capacitor 51 to the red color grid 22. Since the decrease in intensity of the red signal is proportional to the increase of Y signal, the red color is returned to its natural hue.

It will be noted that the red signal was present when the blue signal was added; therefore, the blue color grids 24 were observing both "red" and "blue" signals, and to produce a proper blue color must discount the red signals present in beam 28. Referring again to FIGURE 1, the R signal was simultaneously applied to R amplifier 14 and R amplifier 58. The R amplifier 14 amplified and inverted the signal and applied it to the grid of R controlled amplifier 14a. R amplifier 58 amplified and inverted the signal and applied it through the matrix resistors 41 and 42 to matrix amplifier 63. A negative going

signal was taken from amplifier 63 and fed to the second control grid of B controlled amplifier 15a to reduce the blue signal. For further color control (may be adjustable on a panel by the operator) the blue may be balanced by potentiometer 45, which is connected to the matrix amplifier 63 by the lead 66, and further connected to B color grid 24 by the capacitor 49.

Thus, each color signal will matrix the other colors, as they deepen due to the increase of Y signal as other colors are added. In the consideration of three colors, from which all colors will be obtained, the above discussion may be expanded. In this connection, it will be noted that green amplifiers 16 and 59 are provided. It will be seen that any one color will diminish the other two proportionally to the increase of Y signal. The reductions of the signals will be controlled partially at the screen grids of the controlled amplifiers 14a, 15a and 16a. Thus, the reduction is made at two points; at the screen grids of the controlled amplifiers and through potentiometers 43, 44 and 45.

While a preferred embodiment of the invention has been described using specific terms, such description is for illustrative purposes only, and it is to be understood that changes and variations may be made without departing from the spirit or scope of the following claims.

What is claimed is:

1. In a color television circuit and image tube having a single electron beam, an image screen, a plurality of control electrodes controlling electron flow to the image screen responsive to each color signal, the improvement including, amplifying means, for amplifying each color signal individually, a controlled amplifier receiving each amplified signal, matrix bias means receiving each amplified signal and applying same to the controlled amplifier of each other color signal, and means connecting the controlled amplifier output signals to the color electrodes within the tube.

2. The circuitry set forth in claim 1 including, means connecting the output signals of the matrix bias means to the color electrodes within the tube.

3. The method of applying a bias to the color elec-

trodes of a color television image tube having at least one electron beam and an image screen including, amplifying each color signal individually, applying each such amplified color signal to a controlled amplifier and to matrix bias means wherein a specific signal results in the diminution of the other color signals, applying the output of the matrix bias means to respective controlled amplifiers, and applying the output of the controlled amplifiers to the respective color electrodes.

4. In a color television circuit and image tube having at least one electron beam, an image screen, a plurality of control electrodes controlling electron flow to the image screen responsive to each color signal, the improvement including, first means amplifying each color signal individually, a controlled amplifier receiving each first amplified signal, second means amplifying each color signal individually, matrix bias means receiving each second amplified signal and applying same to the controlled amplifier of each other color signal, and means connecting the controlled amplifier output signals to the color electrodes within the tube, said image screen including, a first plate portion having a plurality of spaced openings therein, a control grid exposed within each opening, a second plate portion having a plurality of corresponding spaced openings therein in register with the first mentioned openings, and a discrete portion of material capable of emitting light of respective different colors exposed within each opening, whereby upon electron bombardment the openings contain the electrons to prevent their spreading to adjacent discrete portions thus avoiding color mixing.
